US0D1070407S

(12) **United States Design Patent** (10) **Patent No.:** **US D1,070,407 S**
(45) **Date of Patent:** **** Apr. 15, 2025**

(54) **AUTO DISPENSER**

(71) Applicant: **Tianxiang Liu**, Guizhou (CN)

(72) Inventor: **Tianxiang Liu**, Guizhou (CN)

(**) Term: **15 Years**

(21) Appl. No.: **29/981,818**

(22) Filed: **Jan. 2, 2025**

(30) **Foreign Application Priority Data**

Dec. 3, 2024 (CN) 202430767916.4

(57) **CLAIM**

The ornamental design for an auto dispenser, as shown and described.

DESCRIPTION

FIG. 1 is a front, right and top perspective view of an auto dispenser showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of illustrating portions of the auto dispenser that form no part of the claimed design.

1 Claim, 8 Drawing Sheets
